UNITED STATES PATENT OFFICE.

BERT EDWARD LANE, OF CAMDEN, NEW JERSEY.

TALKING MACHINE.

Application filed June 12, 1919. Serial No. 303,649.

To all whom it may concern:

Be it known that I, BERT E. LANE, a citizen of the Dominion of Canada, residing at Camden, in the county of Camden and 5 State of New Jersey, have invented certain new and useful Improvements in Talking Machines, of which the following is a specification.

One object of my invention is to provide 10 improved sound conducting means for talking machines which can be made cheaply and durably.

Another object is to so construct my invention that it will permit the free movement 15 of the sound transmitting elements of a talking machine and to avoid undue friction between the several parts.

A still further object is to make the parts 20 of my invention in a manner so that they can be easily assembled or taken apart.

Another object is to so construct my invention that it will be of comparatively light weight but will be of such strength as to withstand hard usage without injury 25 thereto.

These objects, and other advantageous ends which will be described hereinafter, I attain in the following manner reference being had to the accompanying drawings in 30 which—

Figure 1 is a fragmentary elevation of a portion of a talking machine showing in central vertical section my invention as forming a part thereof,

35 Figure 2 is a fragmentary section taken on the line 2—2 of Figure 1,

Figure 3 is a section taken on the line 3—3 of Figure 1,

Figure 4 is a perspective view of an amplifying box or housing which forms a part 40 of my invention,

Figure 5 is a developed form or blank from which the box or housing of Figure 4 is made, said blank being stamped or cut 45 from a piece of sheet material, and

Figure 6 is a top plan view of a roller-retaining ring which forms a part of my invention.

Referring to the drawings, 10 represents 50 a cabinet of a talking machine and may be

made in any suitable form including a platform 11 and a base board 12. The platform 11 is spaced above the base board as illustrated and provides a compartment 13.

A box or housing 14 is made of sheet material bent from a blank form 15, as shown in Figure 5. The form 15 includes two oppositely flared extensions 16 and 17 which project from a central portion 18 and two transverse extensions 19 and 20 which are substantially rectangular. The form 15 is adapted to be bent on the dotted lines 21 and each of the oppositely flared extensions 16 and 17 have edge portions 22 which, when bent upon the dotted lines 23, provide flanges 24 for embracing the bent extensions 19 and 20, as clearly shown in Figures 1, 2 and 4. Each of the portions 22 has small flaps or ears 25 bent therefrom, said ears having holes 26 through which screws 27 can be inserted to secure the housing 14 to the base board 12 within the compartment 13. The extension 16 has a large circular hole 28, and the section 17 has a smaller hole 29. These holes 28 and 29 are so arranged that when the form 15 is bent to provide the housing 14 that their axes will be coincident and vertical. A cup 30 is adapted to fit within the hole 29 and has a flange 31 adapted to rest upon the inner surface of the extension 17 (see Figure 1). In order that the cup 30 be of sufficient depth for the purpose intended, the base board 12 is preferably provided with a cavity 32 into which the lower portion of the cup 30 fits.

The housing 14 constructed as above described will flare forwardly within its width and into this housing fits the rear portion of a sound-amplifying horn 33, said horn flaring forwardly in the usual manner. The rear end portion 34 of the amplifying horn stops short of the rear end portion 35 of the housing 14, as clearly shown in Figure 1, and a sound conducting tube 36 extends 90 substantially vertically through the compartment 13 into the housing 14, said tube passing through the hole 28 and having an aperture 37 in its side adapted to permit the sound to pass into the amplifying horn 95 100

33, as will hereinafter be more fully described. A block 38 forms a closure for the lower end of the tube 36, said block having an upwardly and rearwardly extending curved surface 39 which is substantially tangent to the inner bottom surface of the horn 33 and the inner rear surface of the tube 36 so as to cause the sound, passing downwardly through the tube 36 to be deflected forwardly through the amplifying horn 33. The block 38 has a pivot rod 40 secured therein, said pivot rod being substantially vertical and having a portion projecting into the cup 30. A ball-bearing 41 is interposed between the bottom of the cup 30 and the bottom of the pivot rod 40 and serves to take the thrust and support the weight of the tube 36 and at the same time permit said tube 36 to freely turn.

20 The tube 36 extends through a hole 42 in the platform 11 and has a portion which extends above the upper surface of said platform. A tone arm 43 has a substantially vertical portion 44 which fits within and is secured to the tube 36 by rivets 45 or other suitable means. The tone arm 43 supports a sound box 46 in the usual manner and serves to conduct the reproduced sound into the tube 36 and then outwardly through 30 the amplifying horn 33.

A bearing plate 47 has a hole 48 therein which is in register with the hole 42 and through this hole 48 the upper portion of the tube 36 extends. A cap or cover plate 49 is mounted on the bearing plate 47, and screws 50 secure the plates 47 and 49 to the platform 11, said cap plate 49 also having a hole 41 in registry with the holes 42 and 48 but of smaller diameter than the outer diameter of the tube 36. The portion of the plate 49 which includes the hole 51 is positioned directly above the upper end of the tube 36 and thereby prevents the tube 36 from raising out of its proper position. 45 The bearing plate 47 has a plurality of annularly arranged bearing sockets 52 into which fit the trunnions 53 of bearing rollers 54. The peripheral surfaces of the bearing rollers 54 are adapted to engage the outer surface of the top portion of the tube 36 and retain the tube 36 in a vertical position and permit its free rotation. The upper end portions of the trunnions 53 fit within holes 55 in the roller retaining ring 56. The retaining ring 56 is secured to the plate 47 by screws 57 and permits the plate 49 to be removed in case it is desired to raise the tube 36 for cleaning or repair purposes, it being noted that it is merely necessary to remove 50 the screws 50 in order to permit the entire tone arm and tube 36 to be removed from the cabinet.

The housing 14 can be easily and quickly made by cutting or stamping the form and bending the same into shape. The form 15

can be made of sheet metal or other flexible sheet material and is much more serviceable than a casting and is less liable to fracture even if the same is dropped or during transportation. Further than this, the arrangement of the holes 28 and 29 is such that the parts will be in substantially practical alignment and can be quickly put together. The cabinet 10 can be so made that the cavity 32 can be spaced from the rear and side surfaces of the compartment 13 so as to serve as positioning means for the housing 14; it merely being necessary to insert the housing from the front of the compartment 13 until the cup 30 registers with the cavity 32. 75 The hole 42 in the platform 11 can be made appreciably greater than the outside diameter of the tube 36 so as to compensate for any slight difference in alignment between the several parts and in this manner it is 80 unnecessary for a workman who is erecting or assembling the parts to bother or take time in finding centers, as is usual the custom with constructions of this character made prior to my present invention. 85

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims. 90

Having thus described my invention, what 100 I claim as new and desire to secure by Letters Patent is:—

1. A talking machine including a unitary amplifying horn housing having two holes in alignment with each other and positioned 105 one above the other; a sound conducting tube entering said housing through the upper one of said holes; and means providing a pivotal thrust bearing for said tube and positioned within the other of said holes; substantially as described.

2. A talking machine including an amplifying horn housing having a hole therein; a pivotally mounted sound conducting tube entering said housing through said hole and having an aperture communicating with the interior of the housing, said tube having a pivot rod thereon; and a cup within said housing providing a thrust bearing for said pivot rod; substantially as described. 115

3. A talking machine including a platform having a hole; a base support spaced below said platform and having a cavity in line with said hole; an amplifying horn housing in said space between the platform and base and having a hole in its top in line with the hole in the platform; a sound conducting tube entering said hole in the housing and extending through the hole in the platform; and a pivotal bearing support for 120 125 130

said tube including parts respectively mounted on the tube and housing, one of said parts fitting within said cavity and serving as means for facilitating the positioning of the housing to align its hole with the hole in the platform; substantially as described.

In testimony whereof I have signed my

name to this specification in the presence of two subscribing witnesses.

BERT EDWARD LANE.
